UNITED STATES PATENT OFFICE

2,086,455

ELECTRICAL RESISTANCE

Dale G. Wilson, Fort Wayne, Ind., assignor to
 General Electric Company, a corporation of
 New York

Application October 18, 1934, Serial No. 748,819

7 Claims. (Cl. 201—62)

My invention relates to electrical regulators and more particularly to improvements in resistance regulators of the liquid contact type.

Heretofore electrical regulators of the liquid contact type have practically all consisted essentially of a variable resistance device comprising a resistor element which has variable amounts thereof short circuited by submerging it in a liquid conductor. Such regulators may be termed 10 displacement type regulators, as the varying submergence of the resistor in the liquid displaces corresponding amounts of the liquid. As distinguished from this my regulator may be referred to as a surface-tension type regulator.

15 In accordance with one embodiment of my invention, I provide a resistor element with a relatively slideable electrical contact brush comprising a suitable liquid, such as mercury which is maintained in engagement with the resistor by means of the relatively high surface-tension and 20 negative capillary attraction of the liquid.

By this constructional feature I have produced a regulator which is simpler, smaller and less expensive than displacement regulators of corresponding capacity.

25 An object of my invention is to produce a new and improved electrical regulator.

Another object of my invention is to provide a new and improved variable electrical resistance device.

30 Another object of my invention is to provide a new and improved electrical contact.

A further object of my invention is to provide a variable electrical resistance device having a 35 liquid surface-tension type contact brush.

A still further object of my invention is to provide a novel automatic voltage regulator.

My invention will be better understood from the following description taken in connection 40 with the accompanying drawing and its scope will be pointed out in the appended claims.

In the drawing, Fig. 1 is a sectional view of an operative embodiment of my invention; Fig. 2 is a perspective detailed view of a part of Fig. 1; 45 Fig. 3 is a circuit diagram illustrating an application of my invention to a voltage regulator for a two brush automobile battery charging generator; Fig. 4 is a modification of Fig. 3 in which the regulator is provided with an automatic current limit relay and Fig. 5 is a circuit diagram illustrating an application of my invention as a voltage regulator for a third brush automobile battery charging generator.

Referring now to the drawing, and more particularly to Fig. 1 thereof, I have shown my in-

vention as enclosed in a casing 1 which may be made of any suitable material, such as punched and folded sheet metal. Mounted within the casing 1, in a normally substantially vertical position, is a tubular member 2 which is supported within an insulating base member 3. The tubular member 2 is preferably, although not necessarily, cylindrical in shape and it is composed of nonmagnetic metal which is preferably of the type which is not affected by mercury. One such metal is that which is known in the art as Allegheny No. 88. Insulating base 3 may be composed of hard rubber or "Bakelite"; or the like. Set into the base 3 is a normally vertical resistor element 4 which is shown by way of example as a 15 cylindrical resistance rod which is axially mounted with respect to the tube 2. Resistor rod 4 may be made of any suitable material, such for example as the synthetic resistance material containing silicon and carbon and known to the trade as "Globar". The bottom end of the resistance rod 4 is preferably metal coated, such as by an iron spray, so as to facilitate making an electrical contact therewith. This metal coating is indicated at 5. Below the rod 4 and in 20 contact with the metal coating 5 is a spacer or plug member 6 of suitable conducting metal to which is fastened a binding post 7 which is insulated from the casing 1 by suitable means.

Surrounding the upper part of the tube 2 is 30 a solenoid operating magnet 8, which is normally wound of copper wire, and which has connected in series therewith a compensating resistance 9 having a temperature coefficient of resistance opposite that of the copper so that the temperature coefficient of resistance of the circuit including the coil 8 and the resistance 9 is zero and is consequently independent of temperature. This feature of compensating for the temperature coefficient of resistance of a copper coil of 35 a voltage regulator by means of an opposite characteristic resistance in series therewith is, however, an old feature and in and of itself, forms no part of the present invention. One terminal of the coil 8 is connected to a suitable binding 40 post, or terminal 10, which is insulated from the casing 1 by suitable means and one terminal of the resistor 9 is connected to another similar binding post 11, whereby connections to the operating winding 8 of the regulator may be readily 45 made.

Mounted within the tube 2 is a relatively loosely fitting steel plunger 12 having an integral bottom member 13 provided with an opening therein which fits loosely around the resistance rod 4. 50 55

As shown more clearly in Fig. 2, the bottom part of the plunger 12 is provided with a plurality of openings 14 in the form of curved slots.

Spaced within the plunger 12 is a small quantity of a suitable relatively high surface-tension electrical conducting liquid, such for example as mercury, which is indicated at 15. Due to the physical properties of this liquid it does not run out through the spaces between the bottom 10 member 13 of the plunger, which serves to support the liquid, and the tube 2 and the rod 4 but on the contrary it is held in intimate contact with the tube 2 and the rod 4 by means of its surface tension. Consequently, this body of mercury 15 forms a ring-like or toroidal electrical brush acting as a bridging electrical contact between the tube 2 and the rod 4.

For making the other electrical connections to the variable resistance portion of my regulator 20 I provide a binding post or terminal 16 which is fastened to a steel plug 17 which is in electrical contact with the tube 2.

If desired, a metal washer 18 may be inserted in the plunger 12 above the liquid 15 so as to 25 maintain this liquid in place in the event of violent motion or shaking of the plunger 12.

In order to replenish any of the liquid 15 which may escape from the plunger 12 due to excessive vibration or violent motion of the plunger 12, or 30 for any other cause, there is provided a reservoir 19 of the same liquid in the bottom of the insulating cup 3. Thus with a sufficiently long downward stroke of the plunger 12 the supporting member 13 thereof will be submerged below 35 the surface of the reservoir 19 whereby the liquid will enter the plunger through the spaces between the member 13 and the tube on the one hand and the rod 4 on the other. If desired, a ring-like washer member 20 may be provided 40 on top of the reservoir 19 so as to prevent splashing of the liquid.

The electric circuit through the variable resistance portion of my invention may be traced from the terminal 16 to the plug 17 thence down 45 the metal tube 2 to the outer surface of the mercury ring brush 15 then radially inward through the mercury 15 to the resistance rod 4 and through this rod to the other terminal 7. With this circuit it will be seen that when the plunger 50 is drawn up most of the resistance rod 4 is in the circuit while when the plunger is moved downwardly the length of the resistance rod 4 which is in the circuit is progressively shortened whereby the electrical resistance of the path 55 through the regulator is correspondingly decreased. When the plunger is at the extreme bottom portion of its stroke the bodies 15 and 19 of mercury merge thereby in effect short circuiting the device and producing a negligible 60 electrical resistance through the device.

Due to the fact that my regulator is not a displacement type regulator the net weight of the plunger is a constant for all positions thereof except, of course, the extreme lowermost position 65 when the bottom of the plunger is in the mercury 19. Due to this fact it is necessary to have the range of motion of the plunger take place within the so-called uniform pull zone of the actuating magnet 8 in order that the device 70 will operate satisfactorily as a regulator. By uniform pull zone is meant the zone wherein for a constant energization of the winding 8 the pull on plunger 12 is constant throughout a given range of positions. For an operating winding 75 which is uniformly wound with an even num-

ber of layers of wire and for a plunger of cylindrical or tubular shape and of the same length as the operating solenoid this uniform pull zone will correspond approximately to a range of positions of the top of the plunger 12 from a position 5 about four tenths of the way in the solenoid, from the bottom thereof, to a position about eight tenths of the way through the solenoid. However, it should be understood that I do not intend to be limited to any of these shapes or dimensions 10 and that the plunger may be longer or shorter than the coil and that the thickness or other dimensions of the plunger shell may be varied or the core wound with variable depth of turns or any other expedient known in the art may be 15 used in order to obtain a satisfactory pull curve which is accurate within the specified limits of regulation.

The natural air piston action between the plunger 12 and the tube 2 serves as a damping 20 means for the regulator so as normally to prevent too violent movement of the plunger 12 and so as to adapt the regulator to the time constant of the field circuit of a generator which it may be used to regulate. It should be understood, 25 however, that other methods of damping already known in the art may be used if found necessary.

Solenoid magnet 8 may be wound either for voltage regulator purposes or current regulator purposes, depending upon how it is intended to 30 use the regulator. If the regulator is to be a voltage regulator the coil 8 will be wound with relatively high number of turns of relatively small wire so as to have a high resistance whereas if it is adapted for current regulations it will 35 be wound with a few turns of relatively heavy low resistance wire so as to adapt it to carry the relatively heavy generator current.

In Fig. 3 I have shown my regulator connected for regulating the voltage of a variable speed two 40 brush generator 21 having a shunt field winding 22.

Generator 21 may, by way of example, be a battery charging generator provided on an automobile and as shown it is connected, through a 45 schematically represented conventional reverse current cutout 23, to a storage battery 24 and to load circuits comprising lamps 25 and a horn 26, the latter two being controlled respectively by switches 27 and 28. The terminals 10 and 11 of the operating solenoid of the regulator are connected across the terminals of generator 21 and the resistor terminals 7 and 16 of the regulator are connected in series with the shunt field winding 22 of the generator. With this arrangement, any variation in speed of the generator 21, normally tending to cause a change in its terminal voltage, will cause corresponding changes in the energization of the winding 8 of the regulator, thereby causing the plunger 12 to move up or down, depending upon whether the voltage change was an increase or decrease, respectively, whereby the resistance in the shunt field circuit is increased or decreased, respectively, with the result that the voltage of the 55 generator is maintained at a substantially predetermined normal value, for as is well understood by those skilled in the art, an increase in resistance in the field circuit of a dynamo-electric machine reduces the voltage thereof, while a decrease in the resistance of such a circuit tends to increase the voltage thereof.

Fig. 4 differs from Fig. 3 in that in the load circuit of the generator 21, there is provided a current limit relay 29 having a set of normally 75

open contacts 30 which, when closed, are connected to short circuit a resistance 31 in series with the operating magnet of the regulator 1. If desired, resistor 31 and compensating resistor 9 may be combined as a unit. The relay 29 may be so calibrated as to close contacts 30 when the load on generator 21 tends to exceed a predetermined safe value and as soon as this occurs and the resistance 31 is short circuited the effect on the regulator 1 is of a relatively large increase in voltage due to the fact that the short circuiting of the resistor 31 tends to increase the current flow through the winding 8. This causes the regulator plunger to pull up thereby inserting maximum resistance in the circuit of field winding 22, whereby the voltage of generator 21 is reduced to a minimum value. This obviously reduces the current output of the generator 21 and as soon as the current output falls below the predetermined maximum safe value the relay 29 again opens its contacts 30. If overload conditions still exist on the load circuit of generator 21 the relay 29 will again close its contacts with the result that the relay 29 provides a definite vibratory type current limit for the generator 21. With the arrangement shown in Fig. 4 the complete operation is such that up to the predetermined safe value current the voltage of the generator is maintained substantially constant, whereas as soon as the safe value of current is exceeded the voltage of the generator is dropped to its minimum value, whereby the maximum value current is definitely limited to a predetermined value.

Fig. 5 differs from Fig. 3 only in that the regulator 1 is used for regulating the voltage of a third brush type generator 32. In such case, the terminals 7 and 16 are connected in circuit with the field winding of the generator 32 and the operating magnet terminals 10 and 11 are connected across the terminals of the generator 32. With this arrangement, the regulator regulates the generated current below the third brush setting and the third brush regulates the current to the value determined by the setting.

While I have shown and described a particular embodiment of my invention, it will be obvious to those skilled in the art that changes and modifications may be made without departing from my invention, and I, therefore, aim in the appended claims to cover all such changes and modifications as fall within the true spirit and scope of my invention.

What I claim as new and desire to secure by Letters Patent of the United States is:

1. In combination, a length of electrical resistance material, a movable member in spaced relation with said material, a quantity of electrical conducting liquid carried by said member and in engagement with said material, said liquid having a surface-tension sufficient normally to prevent its running through the space between said member and said material, a reservoir of said liquid at one end of said material, and means for moving said member along said material in order to vary the point of contact with said resistance, said motion having a range sufficient to submerge said support below the surface of said reservoir of liquid whereby any loss in said quantity of liquid will be replenished.

2. In combination, a pair of spaced substantially parallel vertical electrical conductors, a vertically movable member loosely fitted between said conductors, and a body of electrical conducting liquid carried by said member and engaging each of said conductors, said liquid having a surface-tension sufficiently high to prevent its falling through the spaces between said member and said conductors.

3. In combination, a metallic tube, a rod of electrical resistance material substantially axially mounted within said tube, a movable circular supporting member loosely fitted between said rod and tube, and a quantity of relatively high surface-tension electrical conducting liquid carried by said supporting member and forming a ring-like electrical conductor between said rod and tube.

4. In combination, a pair of cylindrical electrical conductors arranged concentrically in spaced relation, a body of mercury, and means in spaced relation with said conductors for partially enclosing said body of mercury between said conductors in such a manner as to maintain electrical contact between said conductors through said mercury.

5. In combination, a normally vertical metallic cylinder, a rod of electrical resistance material substantially axially mounted within said cylinder, a movable circular supporting member loosely fitted between said rod and cylinder, a quantity of relatively high surface-tension electrical conducting liquid carried by said supporting member and forming a ring-like electrical conductor between said rod and cylinder, and a reservoir of said liquid surrounding the bottom of said rod and adapted to receive said supporting member at the bottom limit of its range of motion.

6. In combination, a normally vertical tube of non-magnetic metal, an electromagnet winding surrounding the upper portion of said tube, a base of insulating material closing the bottom of said tube, a rod of electrical resistance material supported by said base and extending into said tube, a hollow solenoid plunger of magnetic material loosely fitted in said tube, said plunger having an opening in the bottom side thereof which fits loosely around said resistance rod, said plunger also having openings in its sides near the lower end thereof, and a quantity of mercury in the bottom of said plunger forming an electrical conducting path between said tube and said rod.

7. In combination, a normally vertical tube of non-magnetic metal, an electromagnet winding surrounding the upper portion of said tube, a base of insulating material closing the bottom of said tube, a rod of electrical resistance material supported by said base and extending into said tube, a hollow solenoid plunger of magnetic material loosely fitted in said tube, said plunger having an opening in the bottom side thereof which fits loosely around said resistance rod, said plunger also having openings in its sides near the lower end thereof, a quantity of mercury in the bottom of said plunger forming an electrical conducting path between said tube and said rod, and a reservoir of mercury surrounding the bottom of said rod and adapted to receive said plunger.
